X-RAY APPARATUS

Oscar H. Pieper, Rochester, N. Y.

Application June 18, 1928, Serial No. 286,213

22 Claims. (Cl. 250—34)

The present invention relates to X-ray apparatus adapted for use in the making of anatomical examinations, such for example, as are required in the practice of dentistry, one object of the invention being to provide an improved apparatus of this class which is compact and effectively insulated so that it can be handled under all conditions of operation without danger of electrical shock.

10 A further object of the invention is to provide an X-ray apparatus of unitary construction comprising an X-ray tube and container therefor and a transformer immersed in a body of cooling and insulating fluid in a second container, the fluid of which preferably surrounds the greater portion of the tube holding container to more effectively insulate and cool the same.

15 A further object of the invention is to provide in apparatus of the class described certain advantageous structural features which will facilitate assembly of the parts, reduction in size of the unit and which will render it comparatively inexpensive to manufacture.

20 To these and other ends the invention resides in certain improvements and combinations of parts, all as will be hereinafter more fully described, the novel features being pointed out in the claims at the end of the specification.

In the drawings:

25 Fig. 1 is a sectional elevation of an X-ray apparatus embodying the present invention;

Fig. 2 is a front elevation of the same with the cover plate removed;

Fig. 3 is a transverse section taken on line 30 3a—3a of Fig. 1, and

Fig. 4 is a diagrammatic view showing the electrical connections for the apparatus.

Similar reference numerals throughout the several views indicate the same parts.

35 The present invention embodies a unitary X-ray apparatus in which a high tension transformer is disposed in a container and immersed in a body of cooling or insulating fluid therein such as a suitable oil, the container having connected therewith and preferably disposed therein in spaced relation to its walls a second container enclosing the X-ray tube and permitting lateral insertion and removal thereof through an opening at the front of the second container normally closed by a removable cover plate.

40 In the drawings 10 represents a container constructed of metal or other suitable material having at its rear side a reduced portion 11 conforming to the general contour of the transformer shown therein. The front portion of the con-

tainer is made larger than the rear portion in order to accommodate a second container 13 which is preferably constructed of suitable insulating material, as, for example, phenol condensation products such as "bakelite." The second container is provided with a closure or cover plate 14 which is made detachable to permit of the insertion within and removal from said container of the X-ray tube, indicated generally at 15. The container 10 is provided with an outwardly turned flange 16 which forms a support for the outwardly turned flange 17 of the tube holding container. A gasket 18 or the like is interposed between the flanges 16 and 17 to afford a fluid tight joint between the same. A similar 15 gasket 19 is interposed between the flange 17 and the cover plate 14. Suitable screws or bolts 20 serve to connect the flanges 16 and 17 as shown in Fig. 3, whereby the two containers are permanently connected together. Additional screws or 20 bolts 21 are adapted to connect the cover with said flanges as indicated in Fig. 1 and may be removed to permit removal of the cover when it is desired to remove the old and insert a new tube within the container 13. In this way the 25 two containers are securely connected independently of the connections for the cover and the oil chamber will thus remain sealed when the cover is removed.

The side and rear walls of the inner or tube 30 holding container are spaced from the walls of the outer container as shown so that the inner container is substantially surrounded by a body of liquid, such as the oil referred to above, which serves as a cooling and insulating medium both 35 for the transformer and the tube holding container.

The transformer comprises a loop-shaped core 22 carrying at its opposite sides the primary coils 23 and the secondary high tension coils 24, preferably four in number, as shown by dotted lines in Fig. 2. The transformer may be secured within the container 10 by any preferred means, such as the supports 25 which are suitably connected with the rear wall of the container. Plate like 40 members 26 and 27 engage the opposite sides of the core 22 to support the same. A suitable number of screws 28 serve to connect the plate like members to the supports 25 whereby the transformer is securely held within the rear portion 45 of the container 10.

The X-ray tube may be of any suitable or preferred type, being preferably constructed in a manner to permit it to be laterally withdrawn from the container 13 by transverse movement 55

through the front of the latter when the cover or closure 14 has been removed. For this purpose the mountings for the tube are so constructed as to permit it to be readily detached without loosening or removing any of the electrical connections between the tube and the transformer. Thus the X-ray tube may be easily removed and a new one inserted whenever necessary by persons who have little knowledge of apparatus of this class.

Within the X-ray tube are indicated generally at 29 and 30 the anode and cathode or ray projecting parts of the apparatus which may be constructed in any suitable or preferred manner and which are properly sealed within the tube.

A stem or terminal rod 31 constructed of copper or other suitable conducting material is joined with the anode and has a right angular portion 32 slidably engaging the terminal mounting 33 with which is connected the high tension winding of the transformer. The mounting is preferably in the form of a metallic sleeve or socket within which the angular portion 32 of the copper rod or stem is telescoped. The sleeve is suitably connected with the rear wall 34 of the tube container, being preferably projected through and anchored therein as shown in Fig. 1. Formed integral with the sleeve is a semi-circular radiator 35 projecting within and cooled by the oil surrounding the transformer as shown in Fig. 1.

The cathode or filament end of the X-ray tube is provided with laterally extending terminal plugs 36 and 37 constructed of metal and connected with the glass tube 15 in any suitable manner.

The incandescent filament 38 is connected with the plugs 36 and 37 by the conductors 39 and 40 respectively. The plugs 36 and 37 are detachably connected with the terminal mountings 41 and 42 secured upon the rear wall 34 of the container and preferably comprising metallic sleeve or socket like members for receiving the plugs as shown in Fig. 1.

The sleeve 41 is projected through the wall 34 and, like the sleeve 33 is so anchored within said wall as to form a liquid tight joint whereby to prevent the escape of oil from the container 10 into the tube holding container 13.

The secondary coils 24 are grounded on the container 10 at 43. The conductor 44 of said coils is extended through an opening in the terminal mounting 33 where it is clamped in engagement with the surface 45 thereof by a washer 46. The washer is preferably constructed of lead or other relatively soft material having the dual purpose of forming a seal for the opening through which the conductor 44 extends and for clamping it in close contact with the surface 45. The lead washer is clamped in position by a screw 47 as shown in Fig. 1, the head of the screw being preferably made large enough to fit the bore 48 of the sleeve 33. The lead washer is preferably of the dished type so that when pressure is applied upon the convex side thereof by the head of the screw the washer will tend to flatten out whereby its peripheral edge will be tightly forced into contact with the wall of the sleeve to form a sealed joint for preventing the escape of the oil into the sleeve.

The opening through the sleeve 41 for the conductor 49 of the transformer is likewise sealed and the end of said conductor is clamped in position upon the surface 50 of said sleeve by the same type of washer and screw described above for the conductor 44 of the transformer.

Metallic plugs 41a and 42a are extended through

the cover plate 14 and are respectively connected with the sleeve-like mountings 41 and 42 by conductors 49a and 40a as shown in Fig. 1, which as will be understood are made long enough to permit removal of the cover plate without having to disconnect the conductors at either end. The plugs are adapted to receive the circuit wires for the filament or cathode end of the tube.

Suitable binding posts 51 and 52 are carried by the container 10 for receiving the conductors 51a 10 and 52a of the primary coils 23 of the transformer. The binding posts are also adapted to receive the wires leading from the supply line as shown in the diagrammatic arrangement of Fig. 4.

The usual detachable cone 14a through which 15 the rays are projected is preferably screwed into position upon the cover plate 14 opposite the target portion of the anode 29 as shown in Fig. 1.

The anode end of the X-ray tube is surrounded by a barrier 34a which serves to prevent surface 20 creeping of the current passing through terminal mounting 33 which might otherwise find its way to the outside metallic container 10 through the end wall of the tube holding container. The barrier is preferably in the form of an upstanding 25 U-shaped wall formed integral with the rear wall 34 of the tube holding container.

The circuit arrangement indicated diagrammatically in Fig. 4 comprises generally the primary and secondary windings 23a and 24a respectively, the latter preferably including four coils as shown by dotted lines in Fig. 2. The secondary ground is indicated at 43, the same being made on the container 10. The cathode heating transformer is indicated at 53, which includes a secondary winding connected to the filament as shown in Fig. 4. The filament control is indicated at 54, and the filament switch at 55. The main supply line switch is shown at 55. The X-ray switch at 57, while an auto transformer 40 is indicated at 58 for adjusting the voltage impressed upon the apparatus.

It will be readily understood that there is a decided advantage in mounting the tube holding container within the transformer container 45 and disposing it within the body of oil or other suitable fluid surrounding the transformer as shown in Fig. 1. In this way a single body of oil is employed to insulate and cool both the transformer and the tube holding container. With this arrangement the tube holding chamber and the tube therein are effectively cooled without having to mount the tube directly within the cooling fluid. One advantage of this is that the tube may be readily removed when desired without first 55 having to draw off the oil in which it is customary to mount the tube. With the present arrangement the entire unit is enclosed in a single casing or container, and all of the operating parts are surrounded by the cooling and insulating fluid 60 whereby more complete protection against electric shocks is afforded both to the operator and the patient while at the same time the size of the apparatus is reduced to a minimum.

Furthermore, by using the inner or tube holding 65 container to close one side of the outer or fluid holding container, the amount of material necessary to construct the apparatus is considerably reduced, and a saving in the cost of manufacture is thereby effected.

By extending the X-ray tube longitudinally of and parallel with the coils of the transformer, and placing the same relatively close together, a comparatively small and compact unit is afforded which is relatively light, and therefore more easily 75

handled. A further advantage lies in the improved right angle terminals or mountings for the tube which not only afford rigid supports for the opposite ends thereof, but permit it to be easily inserted and withdrawn by a transverse movement without disconnecting or detaching any parts other than the closure 14.

The present X-ray unit may be adjustably mounted on or suspended from any suitable supporting means which will permit it to be conveniently controlled, and readily adjusted by the operator in making the desired X-ray examinations from time to time.

I claim as my invention:

15. 1. An X-ray apparatus comprising the combination of a fluid container, a second container closing one side of the fluid container and including a rear wall and a removable front wall, an X-ray tube disposed within the second container substantially in parallel relation to said front wall, separate terminal mountings for the tube extending transversely thereof and secured upon said rear wall, a transformer within the fluid container and conductors connecting the high tension windings of the transformer with two of said terminal mountings.

20. 2. An X-ray apparatus comprising the combination of a main container open at one side and having a projecting flange, a second container disposed within the main container in spaced relation to its walls and having a flange seated upon the flange of the main container, said second container including a removable cover plate, said main container having a body of insulating liquid therein surrounding that portion of the second container projecting therein, an X-ray tube within the second container, said second container having transversely extending terminal mountings connected therewith, a transformer in the main container and connections between two of said terminal mountings and the high tension windings of the transformer.

25. 3. An X-ray apparatus comprising the combination of a fluid container, a second container projecting therein and serving as a closure member and seal for one side of the fluid container, said second container including front and rear walls, the former being removable without breaking said seal, an X-ray tube within the second container supported upon and in parallel relation to said rear wall, a transformer secured within the fluid container and connections between the high tension windings of the transformer and two of the terminals of the tube.

30. 4. An X-ray apparatus comprising the combination of a main container having side and rear walls, a second container forming the front wall of the main container and having an outer removable wall, a transformer within the main container, an X-ray tube within the second container substantially paralleling said removable wall and adapted to project the rays therethrough and connections leading from the high tension windings of the transformer through the wall of the second container to two of the terminals of the tube.

35. 5. An X-ray apparatus comprising the combination of a main container having side and rear walls, a second container forming the front wall of the main container and having an outer removable wall, a transformer within the main container, an X-ray tube within the second container having angularly disposed terminal portions, mountings carried by the second container upon which said terminal portions are free to

slide and conductors extending from the high tension windings of the transformer and connected with two of said mountings independent of said terminal portions.

6. An X-ray apparatus comprising the combination of a fluid container, a second container secured upon the fluid container including front and rear walls, sleeve-like mountings secured upon and projecting forwardly of said rear wall, an X-ray tube within the second container having angularly disposed terminal portions projecting within said sleeve-like mountings and a transformer within the fluid container electrically connected with two of said mountings.

7. An X-ray apparatus comprising the combination of a fluid container, a second container connected therewith and having a wall closing one side of the fluid container, an X-ray tube mounted within the second container upon said wall, the latter having an upstanding barrier surrounding the anode terminal of the tube, a transformer within the fluid container and conductors leading from the high tension windings of the transformer through said wall to two of the terminals of the tube.

8. An X-ray apparatus comprising the combination of a liquid container, a second container having a wall closing one side of the liquid container, terminal mountings secured upon said wall, an X-ray tube within the second container having terminal portions engaging said mountings, a transformer within the liquid container, conductors leading from the high tension windings of the transformer into openings formed in two of said terminal mountings and means connected with each of the last mentioned mountings serving to both bind the conductor thereon and to seal the opening in which it is disposed.

9. An X-ray apparatus comprising the combination of a fluid container, a second container having a wall closing one side of the fluid container, an X-ray tube mounted within the second container and having laterally projecting terminal portions, terminal mountings having their inner ends secured within openings formed in said wall and having sleeve-like portions at their outer ends projecting into the second container and adapted to receive said terminal portions, a transformer within the fluid container, conductors leading from the high tension windings of the transformer through said wall and into openings formed in two of said terminal mountings, binding posts threaded within the last mentioned terminal mountings and adapted to receive the ends of said conductors and washers of relatively soft material interposed between the heads of the binding posts and said conductor ends adapted to both clamp said ends upon the last mentioned terminal mountings and to seal the openings therein.

10. An X-ray apparatus comprising, the combination of a fluid holding container, a second container mounted thereon having a body portion projecting therein and substantially surrounded by the fluid thereof, an X-ray tube carried by said second container and having its terminal portions and ray projecting portion within said body portion and a transformer within the fluid holding container connected with two of said terminal portions.

11. An X-ray apparatus comprising the combination of a main fluid holding container, a second container mounted thereon having front and rear walls connected by side walls, said side and rear walls forming the body of the second

5 container and extending within and substantially surrounded by the fluid of the main container, an X-ray tube disposed within the body portion of the second container arranged to project the rays through said front wall and having 10 separate terminal mountings secured upon and extending transversely of the rear wall, a transformer within the fluid holding container and conductors connecting the high tension windings of the transformer with two of said terminal 15 mountings.

12. An X-ray apparatus comprising the combination of a main container open at one side and having a projecting flange, a second container having a body portion disposed within the main container in spaced relation to its walls and having a flange seated upon the flange of the main container, said second container including a cover plate secured upon its flange, 20 said main container having a body of insulating liquid surrounding the body portion of the second container projecting therein, an X-ray tube having its terminal portions and its ray projecting portion within the body of the second container and a transformer in the main container having its high tension coils connected with two of the terminals of said tube.

13. An X-ray apparatus comprising the combination of a container having a body of insulating fluid other than air therein, a transformer within said container, a second container closing one side of the fluid container and serving to seal the latter, said second container including a rear wall and a removable cover plate 35 through which the rays are projected, an X-ray tube within the second container, terminal mountings for the tube extending transversely thereof and forwardly from said rear wall and detachably receiving the tube, said tube being 40 removable from said mountings by an outward transverse movement and connections between the high tension windings of the transformer and two of said terminal mountings.

14. An X-ray apparatus comprising the combination of a main container having therein a fluid of a high dielectric strength other than air, a second container disposed within the main container and having a wall closing one side of the main container, an X-ray tube mounted within 45 the second container upon said wall substantially in parallel relation thereto, said second container and the tube therein being substantially surrounded by the fluid in the main container, a transformer within the fluid container and connections 50 leading from the high tension windings of the transformer through said wall to two of the terminals of the tube.

15. An X-ray apparatus comprising the combination of a fluid container, a second container 60 secured thereto having a rear wall and a removable front wall, an X-ray tube within the second container having at its anode end a right angle terminal portion and at its filament end a pair of right angle terminal portions, spaced mountings on said rear wall detachably receiving said 65 right angle terminal portions said tube being detachable from said mountings by an outward transverse movement and a transformer within the fluid container electrically connected with the two of said mountings independently of the terminal portions thereof.

16. A device of the character described comprising a main tank serving as a transformer casing, a body of insulating material contained 75 within said main tank, a high tension transformer

mounted within said main tank and insulated therefrom by said body of insulating material, a containing vessel mounted within said main tank, a vacuum discharge tube mounted within said containing vessel, means connected with said vacuum discharge tube for diffusing heat from said vacuum discharge tube into said body of insulating material, and connections from said high tension transformer to said vacuum discharge tube, for energizing said vacuum discharge tube.

17. The combination of a main tank serving as a transformer casing, a high tension transformer mounted therein, a body of insulating material contained within said main tank and covering said high tension transformer, an auxiliary tank detachably connected with said main tank and disposed below the exterior surface of the latter, said auxiliary tank while in position upon said main tank being partially submerged in 20 said body of insulating material and forming substantially two compartments separated by a partition, a vacuum tube housed within said auxiliary tank, and connections from said transformer to said auxiliary tank and said vacuum tube 25 housed therein, for the purpose of energizing said vacuum tube.

18. In X-ray apparatus, a casing containing a volume of cooling and insulating material, an X-ray tube located exteriorly of the casing and 30 provided with spaced electrode terminals, a source of high tension electrical energy housed within the casing and immersed in said cooling and insulating material, mountings on a wall of the casing detachably receiving the electrode terminals 35 of the tube respectively, one of said mountings having cooling means located within the casing and immersed in the cooling and insulating material, and high tension conductors passing through the cooling and insulating material to 40 connect two of said mountings with said high tension source.

19. In X-ray apparatus, an X-ray tube provided with electrode terminal portions, a casing containing a volume of cooling and insulating material, a source of high tension electrical energy housed within said casing and immersed in said cooling and insulating material for energizing 45 said tube, bushings sealed in a wall of said casing, said bushings being provided with recessed portions and two of said recessed portions forming 50 terminals connected to said high tension source, said recessed portions being adapted to receive the electrode terminal portions of said X-ray tube, and one of said terminals having a cooling radiator located within the cooling and insulating material in said casing in heat conducting communication with one of the electrode terminal 55 portions of said X-ray tube.

20. In X-ray apparatus, an X-ray tube including electrode terminals, a casing containing a volume of cooling and insulating material, a source of high tension electrical energy housed within said casing and immersed in said cooling and insulating material for energizing said X-ray 60 tube, spaced bushings secured on a wall of said casing and provided with recessed portions in which the electrode terminals of the tube are detachably extended, said bushings having terminals 65 electrically connected with the electrode terminals of said X-ray tube, and electrical conductors passing through the cooling and insulating material to connect two of said electrical terminals to said high tension source.

21. In X-ray apparatus, a casing containing a 75

volume of cooling and insulating material, a source of high tension electrical energy housed within the casing and immersed in said cooling and insulating material, said casing having a 5 closing wall at one side thereof provided with electrical terminal portions sealed within said wall, an X-ray tube located at the exterior side of said wall and provided with spaced electrode terminal portions detachably connected respectively with said electrical terminals, one of said 10 electrical terminals having cooling means located within the casing and immersed in the cooling and insulating material, and conductors passing through the cooling and insulating material and 15 connecting two of said electrical terminal portions with said high tension source of electrical energy.

22. In X-ray apparatus, an X-ray tube provided with electrode terminal portions, a casing

containing a volume of cooling and insulating material, a source of high tension electrical energy housed within the casing and immersed in said cooling and insulating material, said casing having a wall serving to close one side thereof and 5 provided with electrical terminals for detachably receiving the electrode terminal portions of the tube, one of said electrical terminals being recessed and receiving one of the electrode terminal portions of the tube therein, said recessed terminal 10 extending through said wall and having cooling means disposed within the casing and immersed in the cooling and insulating material, and conductors passing through the cooling and insulating material and connecting two of said 15 electrical terminals with said high tension source of electrical energy.

OSCAR H. PIEPER.
